ALFRED C. DE LORME, OF EAST ORANGE, NEW JERSEY, ASSIGNOR TO SPLITDORF ELECTRICAL COMPANY, OF NEWARK, NEW JERSEY.

IGNITION SYSTEM.

1,258,098.

Specification of Letters Patent.

Patented Mar. 5, 1918.

Application filed May 18, 1917. Serial No. 169,380.

To all whom it may concern:

Be it known that I, ALFRED C. DE LORME, a citizen of the United States, residing at East Orange, in the county of Essex and State of New Jersey, have invented certain new and useful Improvements in Ignition Systems, of which the following is a specification.

This invention relates to an electric ignition system suitable for internal combustion engines and more particularly to engines used in aero and hydro planes. Engines used for such purposes are usually equipped with a main or service magneto for ignition and an auxiliary or starting magneto for the purpose of producing strong sparks at the time of starting.

It is also general practice on aero and hydro planes, where weight is an important item, to use magneto ignition as it has been found to be the ideal ignition after the engine has been started. It is the usual practice in starting engines used for flying to first see that the service magneto is disabled and then turn the crank shaft of the engine over a few times by taking hold of the propeller blades, thus drawing in gas into the engine cylinders and then to operate by hand the auxiliary or starting magneto which is not mechanically connected with the service magneto or any of the driving parts of the engine.

It usually happens that the engine will stop with charges of combustible gas in one or more of the cylinders which may be utilized for starting the engine by causing a spark in one of these cylinders by means of a starting magneto or its equivalent thereby avoiding the necessity of turning the engine over by means of the propeller blades. However, if the engine does not start under this condition then it must be turned over to draw in fuel as above outlined.

Various schemes have been proposed for this ignition work, including a service magneto and a starting magneto, or a service magneto and a battery and vibrating coil in place of the starting magneto, the starting magneto or coil being connected to the service magneto distributor through a trailing brush, or a starting magneto of the low tension type may be used being connected to the primary of the service magneto thereby using the armature of the service magneto as an induction coil.

All of the systems so far proposed are open to various objections, such as large sized starting magneto; the danger of interference of starting magneto with the normal operation of the service magneto; inability of starting magneto to produce sufficient action on the primary of the service magneto when used in this manner; inability of being able to set the timing lever of the service magneto at its best "picking up" position, etc.

It is the object of my invention to provide a system which will overcome the above mentioned and other objections at the same time furnish a system which will be relatively cheap and simple in its general make up.

Other and further objects will be apparent after a study of the following specification and drawing, in which Figure 1 is a diagrammatic representation of one form of my ignition system, and

Fig. 2 is a diagrammatic illustration, on a reduced scale, of a modified form of distributor.

Referring particularly to the drawing, 1 illustrates the service magneto, which is shown as of the inductor type, having field poles 2 and 3 with rotors 4 and 5 rotating therebetween on shaft 6. Across the top of the poles 2 and 3 is a yoke of magnetic material 7 carrying primary winding 8 and secondary winding 9. 10 is the breaker arm carrying the contact 11 adapted to co-operate with a stationary contact 12, the breaker being operated by cam 13 that is fastened to shaft 6. 14 is a starting magneto having parts 15 to 26 inclusive corresponding to parts 2 to 13 inclusive of the service magneto 1. 27 illustrates a switch used for switching the starting and service magnetos into their respective circuits as well as for cutting out the service magneto for the purpose of stopping the engine. The outside end of the primary 8 of the service magneto is connected to the contact stud 28 of the switch 27. The breaker arm 10, carrying contact 11, is connected to the contact stud 29 while contact 12 is connected to the framework of the magneto or ground. The outside end of the primary 21 of the starting magneto is connected to the contact 30. The breaker arm 28, carrying contact 24, is connected to the switch contact 31, stationary contact 25 being grounded. The connections

at the breakers, as shown, may be reversed, if desired. The outside end of the secondary 22 of the starting magneto is connected to the switch contact 32 while the outside end 5 of the secondary 9 of the service magneto is connected to a spindle 33 which constitutes a part of its distributor block 34 which is made up of any suitable insulating material. It will be noted that the spindle 33 10 passes through the outer face of the block 34 and has a clamping nut 35 to hold it in position thereon, the spindle 33 being insulated by the insulator 36 and bushing 37. The outer end of the spindle 33 is connected to 15 switch contact 38; while switch contact 39 is connected to binding post 40 of the distributor 34. The switch arm carries a sector 41 that is adapted to bridge from contact 32 to 39 or from 38 to 39. The same switch 20 arm is adapted to operate a sector 42 that, in its various positions, is adapted to connect the studs 29—30 and 31 or the switch studs 28 and 43 which is cross connected to contact 29 or contacts 44 and 45; the first of which 25 is cross connected to contact 28 and the last of which is connected to the ground.

The switch 27 is shown with sectors 41 and 42 in starting position in which it will be noted that the secondary 22 of the starting 30 magneto 14 is connected from contact 32 to 39 and to terminal 40 on the distributor block 34. On the inner face of the distributor block 34 is a metal segment 46 of suitable size and shape from which the brush 47 carried by the distributor finger 48 connects the current to a metal insert 49, the other end of which carries a brush 50 that is adapted to make contact at the proper intervals with a row of terminals molded in the block 34, 35 two of which are shown at 51 and 52. Another set of brushes and inserts corresponding to 47—49 and 50, but which in the sectional view are not shown, are adapted to collect current from the piece 46 and to distribute 40 this current to another row of contact terminals, two only being shown at 53 and 54. The distributing finger 48 is carried on a distributor gear 55 which is supported and driven in any suitable manner, usually by a 45 gear wheel on shaft 6. The details of the distributor 34 constitute no part of my present invention and are thus only briefly referred to in order to show one method of distribution and the connection of the high 50 tension lead from the switch 27 to the distributor. The particular type of distributor shown is adapted for an 8 cylinder engine, although it will be understood any suitable type of distributor may be used for the purpose. 55

Going back now to the position of the sector 42 corresponding to the position of sector 41 in the starting position of switch 27, it will be seen that the primary 21 of the starting magneto is connected to the breaker 23

through contact 30, sector 42, contact 31 and thence through the contacts 24 and 25 to ground; thus making a circuit of the said primary winding. It is also to be noted that primary 21 is connected through contact 30, 70 sector 42, contact 29 to the breaker 10 and through the contacts 11 and 12 of the service magneto; so that as long as the service magneto breaker is in its closed position no impulse will be produced in the primary of 75 the starting magneto no matter how fast the starting magneto is turned and consequently no matter how fast the circuit breaker arm 23 is opened and closed. It will be understood that the service magneto is so installed on the engine that when the timing lever is in full retard position and the cylinder, for example, on which the magneto is timed is at the upper part of the compression stroke, the breaker points 11 and 12 are just 80 opening, hence any movement of the engine piston beyond this point will hold the breaker points 11 and 12 open for some distance. This is the position under which the engine may be started "on compression" after the 85 piston has gone over dead center. At this time any turning by hand of the starting magneto, which is not controlled entirely by its own breaker arm 23, will give sparks from its secondary directly to the distributor 90 34 of the service magneto. Assuming that there is a combustible charge of gas in the particular cylinder, this will be fired and the engine and the service magneto will begin to rotate. However, it will be noted 100 that no matter how fast the starting magneto is turned the time of producing sparks is controlled by the breaker of the service magneto so that the high tension current delivered by the starting magneto to the distributor is perfectly timed therein. After the engine has attained proper speed or condition of running the switch 27 is thrown to the running position which on the drawing is marked "Run". In this position of the 105 switch 27 the sector 42 is across the contacts 28 and 43 thereby closing the primary circuit 8 of the service magneto through its own breaker points 11 and 12 and the starting magneto has its primary circuit open entirely and the sector 41 has been moved to cross the contact 38 and 39 so that the secondary 9 of the service magneto furnishes 110 sparking current to the distributor 34.

Fig. 2 shows a modified form of distributor in which an annular ring 56 is set in the distributor finger 57 which distributes current to the plug terminals in a manner similar to that heretofore described, but current from the switch contact 39 is connected to 120 a terminal post 58 which carries a brush 59 adapted to run on the disk 56.

It will be seen from the above description that the starting magneto used in my system may be turned as fast and as long as 125 130

- desired without any danger of getting an interference of the sparks, and therefore can be geared up or driven in a manner so as to produce and deliver very effective sparking
- 5 current directly to the plugs through the distributor of the service magneto which is adapted to be switched into service at the will of the operator.
- I may use some other auxiliary source of
- 10 sparking current in place of the starting magneto the same being controlled by the switch and breaker of the service magneto or even the service magneto itself may be replaced by another source of service current,
- 15 it being understood that the control of the system will be substantially as set forth, and while I have shown an adaptation of my system to a magneto of the Dixie type yet it will be understood that it may be applied to
- 20 any other type of magneto and that various modifications and alterations may be made, from the diagrammatic illustration shown, without departing from the spirit of the invention or the scope of the appended claims.
- 25 Having thus described my invention what I claim is:—
1. In an ignition system, the combination of a service magneto having a distributor for distributing current to sparking plugs, a starting magneto for delivering sparking current to said plugs, a switch for interconnecting the service and starting magnetos whereby the current from the starting magneto is sent to said plugs by way of the distributor on the service magneto at intervals under control of the service magneto.
  2. In an ignition system, the combination of a service magneto having primary and secondary windings, a circuit breaker for controlling the circuit of said primary winding, a starting magneto having primary and secondary windings and a circuit breaker for interrupting said primary winding, a distributor, and a switch for switching the secondary of the service magneto out of circuit and the secondary of the starting magneto into the distributor circuit, said switch also serving to switch the said circuit breakers in parallel relationship, for the purpose described.
  3. In an ignition system, the combination of a service magneto having primary and secondary windings, a circuit breaker for controlling the circuit of said primary winding, a starting magneto having primary and secondary windings and a circuit breaker for interrupting said primary winding, a distributor, and a switch for switching the secondary of the service magneto out of circuit and the secondary of the starting magneto into the distributor circuit, said switch also serving to switch the said circuit breakers in parallel relationship, and further serving to switch the secondary winding of the starting magneto out of the distributor circuit and the secondary of the service magneto into the distributor circuit at the same time breaking the parallel connection between the two circuit breakers.
  4. In an ignition system, the combination of a service magneto having primary and secondary windings, a circuit breaker for controlling the circuit of said primary winding, a starting magneto having primary and secondary windings and a circuit breaker for interrupting said primary winding, a distributor, and a switch for switching the secondary of the service magneto out of circuit and the secondary of the starting magneto into the distributor circuit, said switch also serving to switch the said circuit breakers in parallel relationship, and further serving to switch the secondary winding of the starting magneto out of the distributor circuit and the secondary of the service magneto into the distributor circuit at the same time breaking the parallel connection between the two circuit breakers, said switch further serving to open the secondary circuit of the service magneto and to ground the primary for disabling the said magneto.
  5. In an ignition system, the combination of a source of service sparking current, a circuit breaker for controlling the time of delivery of the sparking current, a distributor for distributing the sparking current to spark plugs, an auxiliary source of sparking current, a switch for switching into the distributor the sparking current from the said auxiliary source in place of the service source, said switch also serving to switch the said circuit breaker into a circuit whereby it controls the time of delivery of the sparking current from the auxiliary source as and for the purpose described.
  6. In an ignition system, the combination of a magneto for furnishing service sparking current, a circuit breaker for controlling the time of delivery of the sparking current of the magneto, a distributor for distributing the sparking current to spark plugs, an auxiliary source of sparking current, a switch for switching into the distributor the sparking current from the said auxiliary source in place of the sparking current from the service magneto, said switch also connecting the said circuit breaker into a circuit whereby it controls the time of delivery of the sparking current from the auxiliary source as and for the purpose described.
  7. In an ignition system, the combination of a magneto for furnishing service sparking current, a circuit breaker for controlling the time of delivery of the sparking current of the magneto, a distributor for distributing the sparking current to spark plugs, a magneto for furnishing starting sparking current and having a circuit breaker for causing said sparking current

- to come in impulses, a switch for switching the service sparking current out of the distributor and switching in the starting sparking current, said switch also connecting the 5 two circuit breakers in parallel relationship whereby the current impulses from the starting magneto are properly timed through the said distributor.
8. In an ignition system, the combination 10 with a service magneto adapted to be positively driven and having a distributor for distributing sparking current to spark plugs, and a circuit breaker for timing the passage of the sparking current to said 15 plugs, of a starting magneto adapted to be operated by hand and having a circuit breaker for producing sparking current impulses, and a switch for directing the starting magneto current into said distributor 20 circuit at the same time connecting the two circuit breakers in parallel, so that the current impulses from the starting magneto are properly controlled and timed, for the purpose described.
9. In an ignition system, the combination 25 with a means for producing service current adapted to be positively driven and having a distributor for distributing sparking current to spark plugs, and a circuit breaker 30 for timing the passage of the sparking current to said plugs, of starting means adapted to be operated by hand and having a
- circuit breaker for producing sparking current impulses, and a switch for directing the current from the starting means into 35 said distributor circuit at the same time connecting the two said circuit breakers in parallel, so that the current impulses from the starting means are properly controlled and timed, for the purpose described. 40
10. In an ignition system, the combination with a means for producing service current adapted to be positively driven and having a distributor for distributing sparking current to spark plugs, and a circuit breaker 45 for timing the passage of the sparking current to said plugs, of starting means adapted to be operated by hand and having a circuit breaker for producing sparking current impulses, and a switch for directing the 50 current from the starting means into said distributor circuit at the same time connecting the two said circuit breakers in parallel, so that the current impulses from the starting means are properly controlled and 55 timed, said switch also serving to switch the starting means out of the distributor circuit and the service means into the distributor circuit whereby the service means furnishes the sparking current for normal 60 service conditions.

In witness whereof I affix my signature.

ALFRED C. DE LORME.
